CLAIM

The ornamental design for a motorcycle body, as shown and described.

DESCRIPTION

FIG. 1 is a front, top, and right perspective view of a motorcycle body embodying our new design;

FIG. 2 is a rear, top and right perspective view thereof;

FIG. 3 is a right side elevation view thereof;

FIG. 4 is a left side elevation view thereof;

FIG. 5 is a front elevation view thereof;

FIG. 6 is a rear elevation view thereof; and,

FIG. 7 is a top plan view thereof.

The broken lines shown in the figures represent portions of the motorcycle body that form no part of the claimed design.
